Primary Examiner — Sheryl Lane*Assistant Examiner* — Mark T. Philipps(74) *Attorney, Agent, or Firm* — Bachman and Lapointe PC; George Coury(57) **CLAIM**

The ornamental design for a machine for cutting paper, as described and shown.

DESCRIPTION

FIG. 1 is a perspective view of a machine for cutting paper showing our new design;

FIG. 2 is a left side elevational view thereof;

FIG. 3 is a rear perspective view thereof;

FIG. 4 is a rear elevational view thereof;

FIG. 5 is a right side elevational view thereof;

FIG. 6 is a front elevational view thereof; and,

FIG. 7 is a top plan view thereof.
